UNITED STATES PATENT OFFICE

WILLIAM H. HUTTER, OF FORT WAYNE, INDIANA

ACOUSTIC APPARATUS

Application filed March 3, 1932. Serial No. 596,471.

This invention relates to acoustic apparatus and includes among its objects the provision of novel and improved acoustic apparatus suitable for use in conjunction with a radio set or with any other suitable source for delivering energy to be converted into sound, whereby the acoustic or sound emitting apparatus may be attached to or form members of the radio cabinet or may be constructed as one or more units positionable in desired locations and operable by and controlled from the remotely located radio set; whereby the sound is diffused or distributed instead of being projected in one or more definite directions; whereby the quality and fullness of tone of the sound are improved by novel means; and whereby, in general, to provide such novel acoustic apparatus which is adapted to resonate over substantially the entire audible frequency range and to respond with fidelity to the sound vibrations from such converters as loud speakers.

Other objects and advantages of the invention will be apparent from the following description, and from the accompanying drawings, in which similar characters of reference indicate similar parts throughout the several views.

In the drawings:

Figs. 1 and 2 are perspective views of complementary acoustic units embodying some of the features of my invention;

Figs. 3 and 7 are perspective views of complementary acoustic units embodying other features of the invention;

Fig. 4 is a perspective view of novel complementary acoustic units similar to those shown in Figs. 1 and 2, illustrating a use thereof;

Fig. 5 is a perspective view of a multiple acoustic unit of the type adapted to be remotely positioned in respect of the source for supplying the sound convertible energy; and

Fig. 6 is an elevation of a unit similar to that shown in Fig. 5, but employing a single sound converter or loud speaker to resonate the unit.

In order to accomplish the foregoing objects, I employ acoustic apparatus includ-

ing one or more columns 11 responsive to or adapted to resonate at various or different frequencies in order to amplify or improve the quality or tone of the sounds supplied by sound converters or loud speakers 12 associated therewith and adapted to be supplied with energy for conversion into sound through conductors 13 which may be connected to, for example, a radio, a phonograph, or a combined radio and phonograph, such as shown at 14 in Fig. 4. Where more than one loud speaker 12 is employed in the acoustic apparatus, they may be so arranged and connected that they have the proper phase relation.

The particular size and shape of, and means for obtaining the desired resonance characteristics in the columns 11, and the location of the columns are unimportant, it being only important that the resonance characteristics of each column approximate those of the associated speaker. For example, as shown in Figs. 1 and 2, the columns may take a generally rectangular shape adapted to serve as front and back, top and bottom, or other opposite sides or walls of the radio cabinet 14, see Fig. 4. On the other hand, as shown in Figs. 3 and 5 to 7, the columns may be separate from and even remotely positionable in respect of the source of energy for conversion into sound and may be substantially tubular in shape. These columns also illustrate in Figs. 3 and 7 the complementary units which may be positioned at desired locations, and the multiple units with one (see Fig. 6) or more (see Fig. 5) loud speakers 12 for providing a large baffle area for the sound and for diffusing the sound to attain a space effect as distinguished from the discordant blasts so noticeable and undesirable in known acoustic apparatus.

Illustrative of the means for obtaining the desired acoustic characteristics, the columns 11, as shown in Figs. 5 and 6, may be of different lengths and different sizes, and a loud speaker, associated with each column, is adapted to resonate its associated column (see Fig. 5), or a single loud speaker adapted to set up substantially all of the vibrations for

the fundamental tones and overtones of substantially all qualities is associated with a plurality of such columns of different sizes and lengths. (See Fig. 6.)

- 5 As shown, however, in Figs. 1, 2 and 4, I may select a loud speaker responsive to relatively high frequencies and a speaker of relatively low frequencies and mount the former near an end of a side wall 15, and the latter near an end of a side wall 16 of a column 11, by means of a clamping ring 17 and screws 18. The side wall 15 carrying the high frequency speaker is provided with a plurality of apertures 19 about the periphery of the speaker in order to eliminate sounds of low frequency and to establish an equilibrium of air pressure at opposite sides of the speaker.

- 20 Now to this side wall 15 carrying the high frequency loud speaker, I attach a channel 21 of a suitable sounding board material, such as straight grain spruce, provided with a sound insulating gasket 22 of rubber or felt. This channel has a hard and well polished finish and of course is susceptible to various modifications in shape and construction, such as cross-bracing, sectionalization, and aperturing in order to provide the column with resonance characteristics approximating those of the associated loud speaker and in order to improve the quality of sound emanating therefrom.

- 25 A channel 23 of heavier material is suitably attached to the side wall 16 carrying the low frequency loud speaker to provide a column adapted to be resonated by such a speaker. This column is lined with a suitable sound damping material 24, such as felt or acoustic celotex, and may be provided with drapes 25 arranged to hang from near the top of the column inwardly thereof to absorb sounds of high frequency.

- 30 The columns shown in Figs. 3 and 7 may be constructed to resonate at high and lower frequencies, respectively, as described above.

- 35 As already mentioned, the instant invention contemplates an improved wall for radio cabinets. As shown in Fig. 4, a high frequency column such as the one shown in Fig. 1 may form one side of the radio cabinet 14, and a low frequency column such as that shown in Fig. 2 may form the opposite side of the cabinet 14. When so arranged, I over-50 come cabinet reverberation and the effects of cabinet resonance by cross-bracing between the side walls 15 and 16. As illustrated, the control panel 26 as well as the supports for the radio units may serve this function.

- 40 The acoustic columns may be provided with a cover 27 having a plurality of sound escape apertures or louvers 28 behind which I arrange fine silk to produce a finished appearance. Where desired, the columns may also 45 be provided with openings or slits 29 of de-

sired shapes and designs to relieve the air at the mouth of the speaker.

Thus it will be seen that I have provided acoustic apparatus suitable for use in conjunction with a source from which energy may be supplied for conversion into sound and sound conversion apparatus for converting such energy into sound, the conversion apparatus being associated with resonating columns providing a large baffle area to cause diffusion and distribution of the sound from the conversion apparatus and adapted to provide side walls of a radio cabinet or to be remotely positioned in respect thereof.

Having thus described my invention, what I claim as new and desire to secure by Letters Patent of the United States, is:

1. In acoustic apparatus, a plurality of sound converters adapted to resonate at different frequencies and a sound column for each said converter adapted to be resonated by the associated converter to the exclusion of the other converters.

2. In acoustic apparatus for sound producing means, a sound converter responsive to relatively high frequencies, a sound converter responsive to lower frequencies, and means associated with the first said converter to eliminate sounds of such lower frequency.

3. In acoustic apparatus for sound producing means, a sound converter responsive to relatively high frequencies, a sound converter responsive to lower frequencies, and means associated with the second mentioned sound converter to absorb sounds at relatively high frequencies.

4. In acoustic apparatus for sound producing means, a sound converter responsive to relatively high frequencies, a sound converter responsive to lower frequencies, and means associated with each said sound converter for eliminating the frequencies at which the other said sound converter resonates.

5. The combination of energy emitting apparatus adapted to emit energy for conversion into sound with sound converting means adapted to convert the energy emitted by said apparatus into sound, and sound diffusing means associated with said sound converting means and remotely positioned in respect to said energy emitting apparatus.

6. The combination of sound producing means including a source of energy with a plurality of acoustic columns remotely positioned with respect to said source of energy and adapted to diffuse the sound from said sound producing means.

7. An acoustic apparatus for radio sets comprising a relatively high frequency loud speaker, a low frequency loud speaker, and an acoustic column carrying each said loud speaker and adapted to resonate therewith.

8. The combination of a radio receiving set with an acoustic column at opposite sides

thereof adapted to resonate at different audible frequencies.

9. The combination of a radio receiving set with a relatively high frequency acoustic column forming a side of said radio receiving set, and a low frequency acoustic column forming the opposite side of said radio receiving set.

10. The combination of a radio receiving set with a relatively high frequency acoustic column forming a side of said radio receiving set, a low frequency acoustic column forming the opposite side of said radio receiving set, and means extending between 15 said acoustic columns preventing cabinet reverberation.

11. In acoustic apparatus for radio receiving sets, a plurality of tubular columns adapted to resonate at different frequencies 20 and a loud speaker associated with each said tubular column and adapted to resonate it.

12. In a radio receiving set, a tubular acoustic column and an associated loud speaker remotely positioned in respect of said 25 radio receiving set and adapted to convert energy from said set into sounds of high pitch, and another tubular column and associated loud speaker adapted to convert energy from said set into sounds of lower 30 pitch than that of the first said column and associated speaker.

13. An acoustic apparatus adapted to be used as a side of a radio cabinet, comprising a side wall, a loud speaker carried therein 35 near an end thereof, and a channel member of a material resonating at the frequencies of sounds from said loud speaker and secured to said side wall.

14. A side wall of a radio cabinet and a 40 loud speaker carried in said side wall, in combination with a channel member secured to said side wall and constructed of sounding board material.

15. A side wall of a radio cabinet and a 45 loud speaker carried therein, in combination with a channel secured to said side wall and a sound damping lining in said channel.

16. A side wall of a radio cabinet and a loud speaker carried therein, in combination 50 with a channel secured to said side wall, a sound damping lining in said channel, and sound absorbing means carried between said channel and said side wall.

In witness whereof, I hereunto subscribe
55 my name this 26th day of February, 1932.

WILLIAM H. HÜTTER.

DISCLAIMER

1,912,454.—*William H. Hutter*, Fort Wayne, Ind. **ACOUSTIC APPARATUS.** Patent dated June 6, 1933. Disclaimer filed September 13, 1935, by the patentee.

Hereby enters this disclaimer to that part of the specification which is in the following words, to wit:

Claim 2—"means associated with said converter to eliminate sounds of such lower frequency", except where said means to eliminate said sounds of such lower frequency directly affects the sound per se, as distinguished from energy convertible into sound.

Claim 3—"means associated with the second mentioned sound converter to absorb sounds at relatively high frequencies", except where said means to absorb sounds at relatively high frequencies affects the sound per se, as distinguished from energy convertible into sound.

Claim 4—"means associated with each said sound converter for eliminating the frequencies at which the other said sound converter resonates", except where said means is for eliminating sound frequencies as distinguished from energy frequencies convertible into sound.
